LIQUID FUEL BURNING APPARATUS

John A. Wilson, Detroit, Mich., assignor, by
mesne assignments, to Timken-Detroit Axle
Company, a corporation of Ohio

Application May 18, 1935, Serial No. 22,246

10 Claims.

(Cl. 158—4)

This invention relates to apparatus for burning liquid fuel, and it is more particularly concerned with novel and improved apparatus for burning oil or like fuel in accordance with what has become to be known recently as "wall flame" principle.

The principal objects of this invention are to provide new and improved apparatus for projecting and combusting liquid fuel, and to develop preferred suitable burner constructions and arrangements for carrying out combustion with maximum efficiency.

Prior to this invention, liquid fuel burners have been devised for centrifugally distributing oil from a rotating head and projecting it toward a peripheral impingement wall. In some instances attempts have been made to ignite the fuel at a peripheral ring and maintain the combustion there, so as to operate on the desirable and so-called "wall flame" principle. A burner of this type is shown for example in the patent to Forrest A. Heath, No. 1,886,675.

In most of such prior devices, however, the oil is atomized by the head and thrown in a very fine, and at least partially carbureted spray. In some of these prior devices, the fine spray forms a layer which is intended to be partially separated from the primary air that is supplied by the head for support of combustion. In still others of the prior devices the finely atomized oil is intimately mixed with the air supplied, directly in or immediately adjacent the burner head, and high velocity is relied upon to hold the flame toward the periphery. Where oil and air are distributed in slightly separated layers, as well as where the air and atomized oil are intimately mixed in or near the burner head, difficulty of so-called "flash-backs" has been experienced. This is due either to the continuous or occasional presence of a combustible or explosive mixture in the zone between the peripheral wall and the distributor head. If the velocity of the air draft in such devices becomes lower than the rate of flame propagation from the combustion zone toward the burner the flame will follow the mixed atomized oil back to the burner head or "flash-back" with the result that combustion will take place at the head and not only cause improper operation of the burner to continue but will also often cause the head to be heated to a temperature sufficiently high to "burn" it up.

In the copending application of Milton A. Powers, Serial No. 729,928, filed June 9, 1934, there is disclosed apparatus and fuel burning methods which overcome all of the disadvantages

above mentioned in connection with the prior devices developed for burning liquid fuel. The present invention aims to provide fuel burning apparatus possessing all of the desirable attributes of the constructions disclosed in the aforementioned Powers application and to generally improve and refine certain features of the construction and adapt it for special installations, and to also develop further novel liquid fuel burning apparatus, and heating units.

It is therefore a major object of this invention to provide novel and improved apparatus for burning liquid fuel on the wall flame principle, wherein flashback is completely eliminated without any sacrifice in efficiency of combustion at the flame wall and to greatly increase the efficiency of combustion, heat distribution and heat transfer.

It is a further important object to provide a novel liquid fuel burning apparatus which will permit combustion only at the outer periphery of the hearth and which is provided with a novel oil and air distributor head which will not carbonize or burn out even after long periods of service.

It is another object to provide a liquid fuel burning apparatus in which liquid fuel and air are projected from a distributor head to a peripheral flame ring and in which novel means are provided for maintaining a substantial intermediate zone between the combustion zone and the distributor in which the unatomized liquid fuel and air streams are actually bodily separated a considerable extent to prevent combustion in the intermediate zone.

My invention further aims to provide a novel hot air heating unit having a combustion chamber wherein all the parts are maintained at an efficient heat transferring temperature, and yet in which the air supplied to the fuel burning apparatus is maintained at a temperature sufficiently low to insure efficient burner operation.

It is another object to provide, in a burner and combustion chamber assembly wherein the furnace is divided into a combustion chamber and a combustion-air inlet chamber, novel means for insuring a supply of cool combustion-air to the burner and at the same time insuring escape of heated air from the air inlet chamber.

My invention further aims to provide novel distributor heads for fuel burning apparatus of the wall flame type which allow fresh cool air to eddy through the parts thereof during operation, thereby maintaining them at a temperature sufficiently

low to preclude volatilization of fuel in the head and to also prevent carbonization thereof.

It is a further object to provide, for use in liquid fuel burners of the wall flame type, novel oil and air distributing heads having means for preventing combustion gases from circulating about the points of egress of liquid fuel from the head and for minimizing heat transfer by radiation from the flame to the point of liquid fuel egress from the head.

Further objects of this invention will become apparent as the specification proceeds in connection with the annexed drawings, and from the appended claims.

15 In the drawings:

Figure 1 is a vertical sectional view of the burner of the present invention mounted in a hot air furnace and illustrates certain parts broken away in order to more clearly illustrate 20 the structure involved.

Figure 2 is a front elevational view of the combustion-air conduit or burner shield employed in the device shown in Figure 1.

Figure 3 is the top plan view of the burner 25 shield.

Figure 4 is a fragmental sectional view, taken on a vertical plane intersecting the inspection and combustion air inlet door of the hot air furnace in which the burner of Figure 1 is 30 mounted.

Figure 5 is a bottom plan view of the fan of the device shown in Figure 1 as it appears when removed from the device.

Figure 6 is the top plan view of the fan shown 35 in Figure 5.

Figure 7 is an exploded view of the fan and oil distributor employed in the device shown in Figure 1.

Figure 8 is the top plan view of the oil distributor shown in Figure 1.

Figure 9 is a vertical sectional view of a hot water boiler having a slightly modified form of fuel burning apparatus, also forming part of the present invention, installed therein.

Figure 10 is an enlarged elevational view, with one-half of the device in section, of the fan employed in the device shown in Figure 9.

Figure 11 is a fragmental sectional view of a modified form of fan adapted to be used in 50 the device as illustrated in Figures 1 and 9.

Figure 12 is a front elevation of the device shown in Figure 11.

Figure 13 is a fragmental sectional view of a further modified form of fan, and

55 Figure 14 is the front elevational view of the device shown in Figure 13.

With continued reference to the drawings, wherein like reference characters have been employed to designate like parts throughout the 60 several views thereof, and with particular reference to Figure 1, the hot air furnace includes a vertical cylindrical wall 10 closed at its bottom and having its interior space divided by a hearth structure H into a lower compartment and an upper combustion chamber. Cold air to be heated will be brought in conventional manner into contact with the hot portion of the wall 10 which surrounds the combustion chamber.

As shown in Figure 4, heat generated in the 70 walls of member 10 is transmitted to the rooms of the dwelling, or other space to be heated by means of a jacket 14, which completely encloses member 10 except for a recess 21 provided in one side and is spaced therefrom to provide an air heating chamber. The recessed portion 21 pro-

vides access to an imperforate burner inspection and service door 22 and a screened combustion air inlet opening or door 23. Preferably, there is no other air inlet opening to the space below the hearth, and said space is therefore a 5 completely closed chamber except for the screen 23.

The gases of combustion pass from the upper end of the combustion chamber in conventional manner into an annular member 12 fitted between 10 the wall 10 and the jacket 14 and thence pass to the stack outlet in suitable and obvious manner.

Supported on the interior of combustion chamber 10 by any suitable means, such as a plurality 15 of brackets 41 or the like, is the ceramic hearth assembly H. Supported upon hearth H is a flame ring assembly 43, which is made up of a plurality of connected segments, each of which provides an impact wall 44, a sloping air-deflecting wall 45 and a gutter 46. Molded in the hearth 20 and disposed substantially diametrically opposite each other, are a pair of electrodes E which cooperate with a pair of electrodes 47 mounted in the metal flame ring. The two leads connected to the electrodes are connected to the high side 25 of the ignition transformer (not shown) in the manner shown in copending application Serial No. 731,562, filed June 20, 1934. The hearth and flame ring and igniter assembly just described forms no part of the present invention and therefore will not be further described. Reference may be had to copending applications Serial No. 729,928, filed June 9th, 1934, and Serial No. 731,562, filed June 20, 1934, for a detailed description of this structure. 30

Although the flame ring assembly thus far described may be used without grills, I preferably mount a plurality of grill members 48 upon the upper edge of segments 44, in order to control the flame and to more intimately mix the air 40 with the oil vapors. Grills 48 are in the form of substantially rectangular pans having elongated openings therein and they are secured to the segments by means of a plurality of plates 49 which are welded to the ends of each grill. 45 Grills 48 are shown in more detail in the copending application of Milton A. Powers, Serial No. 729,928, filed June 9, 1934. Each plate 49 is provided with slanting faces 51 and 52 and a double armed tab 53. It is to be observed that face 51 50 of each plate 49 is disposed at a different angle than its corresponding face 52, with the result that the grills may be removed and reversed, so as to dispose them at a different angle, to provide a different combustion condition. The position 55 in which the grills will be installed will depend upon the requirements of the particular installation involved.

Extending into an opening 55 formed in hearth H is a supporting member 56, which is secured 60 to the hearth by means of a plurality of bolts 57 which have nuts 58 turned thereon. Secured to support 56, by means of a clamp assembly 59, and having its shaft 60 extending substantially vertically in a motor 61 which is equipped with 65 an electrical cable assembly 62. Secured to the upper end of motor shaft 60, as by means of a cap screw 64, is an oil distributor D and a fan assembly F. Oil distributor D comprises a flanged disk-like member 65 having a plurality 70 (preferably four) of holes 66 provided therein, in which are fixedly secured oil flinger tubes 67. With reference to Figures 10 and 11 it is seen that the outer ends of the oil flinger tubes incline slightly upwardly and this is done to give the oil 75

an upwardly curving trajectory, as will presently appear. Oil distributor member D also comprises a pressed metal conical cup member 68 which is flanged over the periphery of member 65, and is thereby secured in fluid tight relationship thereto.

Provided on the support 56 adjacent the bottom of member 68 is a stationary oil catch basin 69 having a drain pipe 70 associated therewith for draining away any oil that may inadvertently leak into this part of the device. With reference to Figures 1, 7 and 8, it is seen that the upper part of member 65 is provided with a plurality of openings 71. These openings are provided for the purpose of allowing relatively cool air to circulate through the oil distributor and outwardly under the top of the fan, thereby preventing air from being trapped between the parts and having its temperature excessively raised, which might tend to unduly heat flinger tubes 67. Tubes 67 are accordingly maintained at a temperature sufficiently low to preclude cracking of the oil issuing therefrom with the resulting formation of carbon within the tubes. The lower part of cup member 68 terminates in an upwardly extending flange so as to define an annular oil receiving chamber. Oil is supplied to this chamber from a stationarily disposed conduit 72 which delivers oil thereto from a source at a predetermined constant rate, when the head is operating, in well known manner.

Fan F comprises a generally cup-shaped preferably pressed metal member 73, which terminates in a substantially horizontally disposed flange 74 which is of considerable radial dimension. Flange 74 operates to positively separate the oil and air streams issuing from the head and also prevents the recirculating gases of combustion from entering and diluting the fresh air stream. Flange 74 also materially stiffens the structure. Member 73 is provided with a circular bead 75 for the purpose of stiffening the top of the head, and a plurality of fan blades 76, having beveled inner ends, which are secured to the lower inside surface of member 73, preferably by means of spot welding operations as at 77 and may be of various lengths and spacings and be set at various angles depending upon the size of the hearth and the operating characteristics desired. Four rectangular openings 78 are preferably stamped in the periphery of member 73 and the oil distributor is assembled with the fan so that oil flinger tubes 67 register with openings 78, so that oil projected from the tubes may pass outwardly without restriction. Secured to the upper side of flange 74, and symmetrically disposed with respect to each opening 78, is a curved strip-like member or head 79, which is secured at either end to flange 74 by means of a spot welding operation as indicated at 80. The upper portion of member 79 inclines slightly upwardly as indicated at 81 in Figures 1 and 7, and the function of these members, which constitute hoods, will become apparent as the description proceeds.

Air for combustion is supplied to the fan through apertures in supporting member 56 by means of a shutter mechanism that will now be described. Stationarily mounted in a recess in member 56 is a stationary shutter 83 and an oscillating shutter 84. Members 83 and 84 are provided with rectangular openings which may be overlapped in varying degrees to provide various degrees of effective air inlet area. Member 84 is adapted to be actuated by means of a han-

dle 85 secured thereto, and the latter is adapted to be releasably held in adjusted position by means of a thumb screw 86 cooperating with the lower side of support 56.

It is to be observed that not only are the walls of chamber 10 above burner B heated by direct contact with the flame, but a considerable quantity of heat is conducted downwardly through the walls of member 10 below burner B, with the result that air entering inlet 10 is heated by substantially the entire vertical extent of member 10. The air within the chamber below burner B is likewise heated, and in order to prevent the air in the lower part of the casing 10 from becoming heated to a high degree and thereby impairing combustion, I preferably equip the burner with a shield device, which compels all of the air entering the burner to be drawn from the lower region of the lower compartment, the air passing through the shield also maintaining the motor at a cool operating temperature. This construction will now be described.

With particular reference to Figures 1, 2 and 3, the shield comprises an upright cylindrical member 91 and a cover member 92, the two parts defining an upright cylindrical shell which is open at its top and bottom. Cover 92 is disposed on the side toward opening 23 and it is provided to give ready access to the motor. Cover 92 is adapted to be releasably held in place on the shield proper by a suitable means, such as a plurality of thumb screw assemblies 93. The shield is adapted to be held in position in the mechanism by means of a plurality of brackets 94 secured at 120° intervals on the inner wall 35 of the shield. Brackets 94 are apertured and are mounted over bolts 57 and have nuts 95 turned up against them to maintain the shield in position. It is apparent that when thumb screws 93 are loosened and cover 92 removed nuts 95 may be loosened and cover 92 removed to clear support 56 and be removed from the mechanism.

Operation

With reference to Figure 1, assuming that the motor has been started, oil has been admitted to pipe 72, and that igniters E are energized, the operation is as follows. Air is sucked in through screened opening 23, passes upwardly inside of shield 91 through shutters 83 and 84 and then is blown by fan blades 76 outwardly in close contact with the upper surface of the hearth until it strikes deflecting wall 45 of flame ring 43. After the air current strikes wall 45 it is deflected upwardly over gutter 46 and into grills 48 as generally indicated by the arrows in Figure 1.

Simultaneously with the air discharge in the manner just described, oil is centrifugally thrown from flinger tubes 67, and with reference to Figure 1, it is seen that the oil takes an upwardly curving trajectory, as indicated by the dot-dash lines in Figure 1. As the interior of each tube 67 is comparatively smooth, and no restricting orifices are present, the oil is discharged in the form of comparatively large droplets, which strike impact wall 44 of flame ring 43 with a considerable force, which mechanically breaks them up into fine particles or atomizes them.

Both air and oil travel has now been traced to the vicinity of the upper edge of the impact wall of the flame ring, the air flowing over the edge and the relatively large oil droplets impinging at some level below this edge. A part of the oil gravitates downwardly and is ignited by the electrodes. The oil gravitating down- 75

wardly is ignited by the electrodes and a comparatively cold flame starts to burn in trough 46. As combustion proceeds, the heat released by the flame burning in the gutter vaporizes the 5 impinging oil, which mixes with the air and burns and produces a hotter flame. This concentrated heat release rapidly heats the impingement walls; more oil is vaporized; and the flame enlarges in size, a portion still remaining in the 10 ignition groove or gutter but an increasing amount of flame now starts to appear above the segment behind the impingement wall. Shortly, the rate of vapor release is so high, and the amount of vaporized oil in the groove so large, 15 that the flame entirely leaves the groove and rises to the region above and behind the segment. With reference to Figure 1, it is seen that the flame ring and grill assembly is spaced a considerable distance from wall 10, so as to allow 20 the flame to expand in size and thereby impinge upon and distribute its heat over a large area of the surface of the combustion wall. This also prevents the combustion chamber walls from being heated to excessively high temperatures, 25 of course in a hot water or steam system the rate of heat transfer from the combustion chamber walls to the water is so great that the flame ring can be disposed closely adjacent thereto.

When the vapor release rate has increased to 30 a point where the flame entirely leaves the groove, as just described, the impingement wall has reached a temperature where all of the oil is vaporized immediately upon impingement with wall 44. Therefore, when stable combustion conditions have been attained, and the igniter mechanism has been automatically shut off, the vapor content of groove 46 is so high that insufficient air is present to effect combustion therein, and combustion is confined solely above and outwardly of the grills.

With the burner operating under stable conditions in the manner just described, it is to be observed that a constant supply of cool air is supplied thereto by reason of shield 91 drawing 45 air from the bottom of the lower compartment, and through the lower portion of screened opening 23. In view of the fact that the walls of member 10 are not water backed, as in a hot water or steam system, it is apparent that there 50 will be a considerable transfer of heat by conduction downwardly in walls 10, with the result that the air in the lower compartment would become heated to a high temperature if it were not for some circulating system. By providing the 55 shield 91, and extending opening 23 substantially to the lower surface of the hearth, a natural circulating system is established, because a part of the air entering the lower portion of opening 23 passes upwardly over the heated walls of member 60 10 and finds its way over the bottom surface of the hearth and outwardly through the upper portion of opening 23 in the manner indicated in Figure 1. Therefore, the lower compartment is maintained at a comparatively low temperature, and as motor 61 is disposed in the path of incoming cool air, it is maintained at an efficient 65 operating temperature. It will be moreover appreciated that if shield 91 were dispensed with, the air supplied to the shutter assembly would 70 be taken directly from the upper part of the lower compartment, the hottest air space therein, and it would not only subject the parts of the mechanism to a high temperature, but it would also produce carbonization in the ends 75 of flinger tubes 67. Slots 99 and 100 are pro-

vided in cover 92 to allow lever 85 and cable 62 to project therethrough.

It is also to be observed that during normal or stable operation of the burner, flange 14 on the fan assembly deflects the discharge from 5 blades 76 downwardly below a substantially horizontal plane. In other words, flange 14 causes the air to be discharged from the fan in a downwardly curving sheet. The combustion air is thereby segregated from the oil droplets discharged from flinger tubes 67, with the result that the oil droplets are deprived of an environment which would be conducive to ignition until they have reached the impact wall. It will be appreciated that during operation of the burner 15 and distributor head heat is transmitted by radiation inwardly and is directed against the top and sides of fan 73, with the result that if a dead air space were present in the head, flinger tubes 67 might be heated up to the cracking 20 point of the fuel. To overcome this feature, holes 71 have been provided in the upper side of the oil distributor, with the result that eddy currents will seep upwardly along shaft 60, through the distributor, and thence through 25 openings 71 into the space between the distributor and the fan head. These eddy currents circulate about the parts and ultimately find their way out of the assembly under flange 14, and although their velocity is not comparable to the 30 velocity of the major volume of combustion-air leaving blades 76, sufficient air flow is nevertheless present to prevent the parts from attaining temperatures sufficiently high to heat flinger tubes 67 to the cracking point of the fuel or 35 sufficiently high to cause depositing of carbon.

In connection with the feature of heat radiation from the major combustion zone above the grills, it should be observed that hoods 79 also assist in maintaining the flinger tubes 67 at a 40 low temperature by protecting them from radiated heat. With reference to Figure 1, it is apparent that hoods 79 are interposed between the outer ends of flinger tube 67 and the concentrated flame above the grills with the result that 45 the tips of flinger tube 67 are maintained at a low temperature. Although hoods 79, by reason of radiated heat may be raised to an elevated temperature, this heat cannot be transmitted to flinger tube 67 because the parts are spaced and 50 also moving air currents flow therebetween. Hoods 79 also perform the function of cooperating with flange 14 and head 73 to define in effect fan blades which tend to deflect the recirculation gases from around the tubes and also 55 more positively insure that such gases will not dilute the fresh air stream.

Although I find shield 91 to be of particular value in connection with the hot-air furnace units, because the walls of the combustion chamber are maintained at a much higher temperature than in a hot-water heating plant and therefore render the problem of feeding cool air through the burner more difficult, it is to be understood that if desired shield 91 may be used 60 in connection with a steam or hot-water heater burner, and the appended claims are intended to cover my novel shield and burner assembly 65 when used in this connection. In the embodiment shown, it should be particularly observed 70 that shield 91 protects the burner motor against heat radiating from the walls of chamber 10 below the hearth, which, in view of the fact that a hot air furnace is involved, are heated to a 75 comparatively high temperature.

Referring now to Figures 9 and 10 of the drawings, I have illustrated a hot-water heating unit designated generally as W, and although the burner unit as a whole is similar to that just described, it is mounted on a metal hearth assembly designated generally as H' which is supported on a flange 101 formed on boiler unit W. In this view, the manner in which fuel is delivered to conical portion 68 of distributor head D is more clearly shown and it takes the form of a curved pipe 102 which is secured to a stationary part of the burner and aligns with supply conduit 72.

With particular reference to Figure 10, the beveled inner ends of blade 76 are more clearly disclosed and a member 103 is shown as being welded to the top of member 73. Member 103 is a balancing mass which is applied to the fan after a static balance test thereof has indicated the proper position for the mass to be applied to secure proper balance of the fan. This device functions in substantially the same manner as that previously described and it will therefore not be again set forth.

With reference to Figures 11 and 12, there is shown a modified form of fan, which may be used with either of the burner constructions just described. Fan 73a is generally cylindrical in form and is provided with a small diameter cylindrical part 105 in which registering apertures 106 are provided for the four flinger tubes 67. Preferably the metal struck out of apertures 106 is bent outwardly to provide tabs 107. Fan head 73a is also provided with a large diameter portion 108, in which are struck outwardly a plurality of fan blades 76a.

In this form of the invention the oil and air are thrown outwardly toward the flame ring assembly in much the same manner as in the embodiments of the invention previously described, and tabs or lips 107 operate to provide a semi-quiescent zone adjacent the tips of tubes 67 for preventing combustion gases from being sucked back into the head. Tabs 107 also protect the tube tips against radiated heat. In this form of the invention no flange is necessary as blades 76a are located outwardly a considerable distance beyond the tips of tubes 67 and hence no tendency of the oil and air to commingle is present.

Referring to Figures 13 and 14, I have illustrated a further modified form of fan which may be substituted for those shown in Figures 1 and 9, and in this form of the invention fan head 73b is provided with a single cylindrical portion 111 in which flinger tube apertures 112 are provided. Apertures 112 are preferably formed by striking a tab out of the body of flange 111 and the tab is bent downwardly to provide a lip 113. Flange 111 is also provided with a plurality of fan blades 76b which operate to project a blast of air toward the flame ring assembly in the manner described in connection with the first form of my invention.

This form of the invention operates in substantially the same manner as those previously described, and tabs 113 in this form of the invention operate to prevent drafts of air from blades 76b from commingling with the oil droplets projected from tubes 67, as the tube tips are located a radial outward distance which is substantially equal to the radial extent of blades 76b.

With reference now to all of the forms of my invention, it is to be understood that a part of the air located between the top of the fan head

and the upper surface of the oil distributor may flow downwardly through the outermost of openings 71 and find its way into flinger tubes 67, through which it is centrifugally discharged. This very slight air flow further cools the tube tips and it is not effective to break up or atomize the oil therein as the oil flows in a smooth stream along one side of each tube and maintains its unatomized condition.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. In a liquid fuel burning apparatus, a combined air and liquid fuel projecting device mounted for rotation about a substantially vertical axis, a carbureting wall cooperating with said device, said device having means for projecting fuel and air streams in substantially horizontal offset planes toward said carbureting wall; and baffle means provided on said device between said planes and protruding materially beyond the point of discharge of the fuel stream for positively separating said air stream from said oil stream in the region of said device.

2. The apparatus described in claim 1, wherein in said last-named means comprises a substantially horizontal baffle member disposed between the levels of egress of air and oil from said device and extending beyond the locus of discharge of the air stream.

3. In a liquid fuel burning apparatus of the wall flame type, having a substantially horizontal hearth surrounded by a wall to be heated; a substantially endless carbureting member located above the hearth and adjacent said wall, said member having a fuel impact surface facing toward the center of the hearth; a distributor head projecting upwardly through the hearth center and spaced from said carbureting member; said head having means for delivering a disc-like blast of air outwardly along the hearth toward the carbureting member; and said head further comprising means for substantially radially projecting liquid fuel toward said impact wall in unatomized condition from the head, said fuel projecting means being in close proximity to said air delivering means and having a baffle device thereon projecting radially beyond the locus of fuel discharge for precluding admixture of the fuel and air at least during initial travel between the head and the carbureting member, whereby said fuel is caused to impinge upon said impact wall in the form of large unatomized droplets.

4. In a liquid fuel burning apparatus of the wall flame type, having a substantially horizontal hearth surrounded by a wall to be heated; a substantially endless carbureting member located above the hearth and adjacent said wall, said member having a fuel impact surface facing toward the center of the hearth and adjacent which combustion is adapted to take place; a distributor head projecting upwardly through the hearth center and spaced from said carbureting member; said head having means for delivering

5 a disc-like blast of air outwardly along the
hearth toward the carbureting member; and said
head further comprising means for substantially
radially projecting liquid fuel toward said im-
5 pact wall in unatomized condition from the head,
said fuel projecting means being in close proxim-
ity to said air delivering means but spaced ver-
tically therefrom and comprising at least one
10 outwardly directed tube designed to discharge the
fuel without interference with the head structure
whereby said fuel is caused to impinge upon said
impact wall in the form of large unatomized
15 droplets, and means provided on said distributor
head for minimizing transfer of heat to the
outer end of said tube by radiation from the
region of said fuel impact surface, to thereby
preclude volatilization of fuel in said tube.

5. The apparatus described in claim 4, wherein
said last-named means is constructed and located
20 to prevent combustion gases from circulating into
contact with the outer end of said tube.

6. In a liquid fuel burning apparatus of the
wall flame type, means providing an elongated
25 vertical chamber; a horizontally disposed hearth
mounted in said chamber and dividing the latter
into an upper combustion chamber and a lower
combustion-air-inlet compartment, said compart-
30 ment having means for admitting cool atmos-
pheric air to its interior at a point adjacent the
bottom of the compartment and for discharging
warm air from the compartment at a point ad-
jacent the lower surface of said hearth, said
35 hearth having a substantially centrally disposed
aperture and being otherwise air-tight, a flame
ring assembly mounted on said hearth adjacent
its periphery, an oil and air projecting device
disposed on said hearth and located over the
40 aperture therein, means associated with said de-
vice for projecting a substantially unatomized
stream of oil and a sheet of air toward said flame
ring assembly with the oil stream separated
from the sheet of air, and an upright air director
45 registering with the aperture in said hearth and
extending a considerable distance below the lower
surface of said hearth for drawing air into said
oil and air projecting device from the lower part
of said compartment.

7. The apparatus described in claim 6, wherein
said oil and air projecting device comprises an
50 electric motor disposed in said air director and
constructed and arranged to be cooled by air cur-
rents passing upwardly through said director.

8. In a liquid fuel burning apparatus comprising
means forming a vertical chamber and a
55 horizontally disposed hearth mounted in said

chamber and dividing the latter into an upper
combustion chamber and a lower combustion-air-
inlet compartment, said compartment having an
air intake opening in one of its sides extending
from a point adjacent the bottom of the com-
partment substantially up to the lower surface of
5 said hearth, said hearth having a substantially
centrally disposed aperture and being otherwise
air-tight, a flame ring assembly mounted on said
hearth adjacent its periphery, an oil and air pro-
jecting device disposed on said hearth and lo-
cated over the aperture therein, means associ-
ated with said device for projecting a substan-
tially unatomized stream of oil and a sheet of air
10 toward said flame ring assembly with the oil
stream separated from the sheet of air, and an
upright air director registering with the aperture
in said hearth and extending downwardly a con-
siderable distance below the lower surface of said
hearth for drawing air into said oil and air pro-
jecting device from the lower part of said com-
partment, said opening permitting any hot air
15 that may be present between said director and
the walls of said compartment to flow from the
latter at a level above the downwardly extending
end of said air director.

9. The construction described in claim 8,
wherein said air director comprises a vertically
20 divided shell having means for detachably secur-
ing the parts thereof together in substantially
air-tight relationship, one of said parts being
disposed adjacent said air intake opening so that
upon removal it affords access through the latter
25 to the interior of the shell.

10. In a liquid fuel burning apparatus of the
wall flame type, means providing an elongated
vertical chamber, a horizontally disposed hearth
mounted in said chamber and dividing the latter
into an upper combustion chamber and a lower
30 compartment, said compartment having means
for admitting cool atmospheric air to its interior
at a point adjacent the bottom of the compart-
ment and for discharging warm air from the
compartment at a point adjacent the lower sur-
35 face of said hearth, said hearth having a substan-
tially centrally disposed aperture and being other-
wise substantially air tight, an oil and air pro-
jecting device disposed on said hearth and located
over the aperture therein, and an upright air
40 director registering with the aperture in said
hearth and extending a considerable distance
below the lower surface of the latter to receive
and convey cool air upwardly into said projecting
device.

JOHN A. WILSON. 55
